UNITED STATES PATENT OFFICE.

MONTFORD MORRISON, OF CHICAGO, ILLINOIS.

ELECTRON DISCHARGE APPARATUS.

Application filed January 12, 1924. Serial No. 685,801.

My present invention relates to devices which operate with the assistance of incandescent cathodes and has particular reference to such devices where the discharge produced is subject to variations in behavior due to changes in gas ionization within the devices, differences in specific electron emissivity and instability of spontaneous electron liberation.

10 Among the objects of my invention are: first, to provide means for stabilizing the electron discharge of the apparatus when the source of electric current for heating the aforesaid incandescent cathodes is subject to variation; second, to provide an improved constancy of conductivity within the device when the said device is subject to gas ionization; third, to provide an improved constancy of the electric conductivity in the device when the specific emissivity of the incandescent cathodes is subject to variation; fourth, to provide an improved constancy of conductivity of the device when spontaneous ionization may be present or subject to variation.

Other and further objects will be in part pointed out and in part obvious upon reading the specifications and inspecting the drawing, but the novel scope of my invention will be pointed out with certain particularities in the appended claims.

For a clear understanding of my invention reference may be had to the following description bearing connection with the accompanying drawing in which the figure is a general and diagrammatic view of one embodiment of my invention.

It is admitted that the art of controlling electron discharge apparatus by means subject to the discharge current through the tube is not new. Such apparatus has been in extensive use in connection with discharge tubes operating with pure gas ionization and in those in which only non-gas ionization is alleged to occur. In thermionic X-ray tubes such devices have been depended upon principally to eliminate variations in the exciting current of the cathode filaments caused by supply-line voltage-fluctuations.

50 The most important use of my device, however, is not for the elimination of line variation in exciting-current of the filament of an X-ray tube but the elimination of erratic behavior in X-ray tubes employing

hot cathodes. Although these tubes are alleged to be independent of gas ionization, experience in the art shows that there is an appreciable amount of gas nearly always present and that the actual pressure of this gas can vary from instant to instant. There 55 may be produced considerable gas ionization at times and sufficient to injure the tube if not promptly taken care of, when it occurs in over-abundance. The effect of this gas ionization is to increase the conductivity of 60 the tube, that is, with a constant filament temperature the conductivity may rise or 65 lower of its own accord.

The objects of stabilizers of the prior art 70 for electron discharge tubes have been particularly directed toward the stabilization of X-ray tubes when the operation is supposed to take place independently of gaseous ionization, and their principal objects have been 75 to provide means for automatically regulating the electron emission, particularly when the source of heating-current for the incandescent cathode varies in voltage due inherently to line fluctuations and it was thought that this was the principal source of 80 operative erraticness in these tubes. However, I have discovered that there are four sources of variation in the electrical conductivity of these tubes and that the principal 85 difficulty does not originate from a variation in filament excitation voltage, but from variation in the aggregate electron emission from the four sources.

The four sources which I have discovered 90 are variations in the temperature of the cathode, variations in the specific electron emissivity of the hot cathode itself, variations in the gas pressure within the tube which not only affect the gaseous ionization but also the electron emission of the filament itself, 95 as well as does it even change the spectrum of the target due to interference with the velocity-distribution of the electron stream, and also variations in spontaneous ionization which is the pulling out of electrons 100 themselves from parts of the cathode on which the electrostatic stresses are concentrated, due to points, sharp edges and the like.

It will be appreciated by those familiar 105 with the art that in view of this explanation, it is erroneous to assume that the stabilization of any one of these phenomena will af-

fect stabilization of the discharge current through the tube itself; and further, that if the discharge current is to be stabilized the aggregate electron liberation must be made 5 constant as a whole and this may be done by selecting one of the predominating factors of the aforementioned group which may be controlled external of the tube and construct a device which will add to or subtract 10 from the value of this selected factor in such a way as to maintain the aggregate at a substantially constant value.

Means and methods for doing this are the substance of this invention.

15 In all the devices of prior art, some sort of a relay has been used to accomplish their result. In the first case on record, a simple relay element in which the armature is actuated by the discharge current through the 20 tube is made to operate an osmosis regulator which lowers or raises the conductivity of the said tube. In other developments of the relay element above described instead of being actuated by intermittent currents is 25 made to vibrate synchronously with the alternation of the line voltage and this vibrating action being utilized to accomplish stabilization of the discharge current.

In my device I eliminate all vibrating and 30 relay parts such as used in connection with the case of the vibrating armature which is supposed to operate synchronously with the line voltage. The performance imposed 35 upon this instrument and the limits of variations in its behavior result in this being almost impractical as an operative device and its use in the art has for this reason been largely abandoned.

40 In the present invention I employ a special circuit for the excitation of the hot cathode of the electron discharge tube, such that aggregate electron liberation in the said tube is maintained substantially constant by the discharge-limitation characteristics of the circuits involved.

45 Referring to the figure, 1 is a source of alternating potential which through leads 2 and 3 supply the primary 4 of the step-up transformer 5 with electrical energy. This described circuit may have a means 6, 50 of varying the induction within the core of the said transformer, and said circuit may be supplied with a switch 7, for practical purposes.

55 The aforesaid variations in the induction of the core transformer 5 produce different potentials in secondary 8 of said transformer.

60 High potential leads 9 and 10 conduct current to the alternating current terminals 11 and 12, of the rectifier 13, preferably of the kind set forth in my United States Letters Patent 1,466,541, and 14 and 15 are the direct current terminals of said rectifier; the terminal 14 conducting current by

means of lead 16 to the anode terminal 17 of the X-ray tube 18, preferably enclosed within the shield 19, as set forth in my application Serial Number 633,712, filed April 21, 1923.

70 Direct current terminal 15, by means of lead 20, conducts negative potential to my stabilizing apparatus, as will be more fully hereinafter described.

75 Rectifier 13 is driven synchronously with the source of alternating potential 1, by mechanical connection, or by electrical means, such as a synchronous motor 21, operating from source of alternating potential 1, through leads 22 and 23, the circuit of which 80 may be supplied with a switch 24.

85 Of course, in practice, the synchronous motor 21 would be connected mechanically to rectifier 13, but this connection is omitted in the diagram for the sake of clearness.

90 The source of alternating potential 1 also supplies insulation to transformer 25, by means of leads 26 and 27, with operating current for said transformer, the primary circuit of which may be supplied with the 95 switch 28.

95 The function of the insulation transformer 25 is to provide electrical insulation between the corona-proof housing 29 and the source of alternating potential 21. It is not requisite of the invention that alternating source of potential 1 be insulated by means of a transformer, nor that the transformer be employed at all. It only 100 happens that in the illustrated embodiment of this invention it is convenient, and the fact will be more fully pointed out and apparent upon the description of the contents of the corona-proof housing 29.

105 The secondary 30, of insulation transformer 25, supplies electrical energy for transformer 31, which is preferably of a high reactance type, or it may be supplied with external resistance or reactance 32, to limit the short circuit current of the said 110 transformer.

115 Transformer 31 is provided with secondary 32 which, by means of leads 33, supplies heating current for the cathode 34 of X-ray tube 18.

120 Transformer 31 is provided with a tertiary winding 35, which is shunted by an adjustable critical-voltage breakdown-device 36, such as a spark-gap, or the like. The said tertiary winding is further shunted by a condenser 37. The tertiary winding 35, spark-gap 36, and the condenser 37 constitute a divided circuit for negative current passing from rectifier terminal 15 through lead 20; thence divided through 125 these aforesaid three circuits and to cathode 34.

130 The function of the high-resistor 39 is that it serves to assist in the building up of the voltage across spark-gap 36, to cause

synchronous spark-over therebetween, due to current flow from lead 20, to the cathode of the X-ray tube 18. This forced flow of current through the tertiary winding of 5 transformer 31 is such that the variation in magnetic flux due thereto does not seriously affect the voltage of secondary 32, or said variation may be made to raise or lower said voltage somewhat without interfering 10 materially with the operation of my device.

The condenser 37 is not an essential element of my invention, but in some cases improves the operation thereof.

In the functioning of my device the operation is as follows:

Alternating source of potential 1, set into operation, switch 28 is closed. Potential is induced into secondary 30 of transformer 25, which in turn excites transformer 31, 20 which in turn supplies potential for secondary 32, which supplies the heating current to cathode 34 of X-ray tube 18. The X-ray tube 18 thus is supplied with thermionic electron-conductivity. Switch 24 is closed, 25 which sets synchronous motor 21 into operation, which motor being mechanically connected to rectifier 13 drives the said rectifier at its proper speed, phase relation and polarity. The rectifier is then in readiness 30 to produce high-tension direct current for the X-ray tube 18.

Adjustment 6 of transformer 5 is selected to give the proper potential in secondary 8; switch 7 is closed. Direct current terminals 35 14 and 15 of rectifier 13 are then supplied with high potential unidirectional current.

The normal voltage induced into tertiary winding 35 by excitation of primary 38 is not sufficient to cause spark-over at the gap 40 36. As the current from lead 20 is conducted through high resistor 39, through tertiary 35, thence to the cathode 34, the voltage across the gap 36 rises in proportion to the said current flow, and hence when the 45 current value of the cathode 34 rises to a predetermined value, spark-over at the gap 36 occurs, in the absence of condenser 37, which has not been so far described. This 50 spark-over of gap 36 short-circuits the tertiary winding 35, which reduces the magnetic induction in the core of the transformer 31, because of the high reactance characteristics of the primary circuit heretofore described. Thus the voltage of secondary 32 is reduced and hence the excitation 55 current filament 34.

It will be appreciated by those familiar with the art that this is a cyclic process and this spark-over occurs during each half cycle 60 of the alternating current exciting the filament 34. That is, as each half lobe of the alternating current through filament 34 begins to build up in value, it is only allowed to continue to flow according to its normal 65 sinusoidal law until the discharge current

through the tube has risen to the predetermined value, causing spark-over at 36, so that the filament exciting current is choked off, so to speak, during each half cycle when the discharge current through the X-ray 70 tube has reached its predetermined value. This definite reduction of excitation current produces the current limitation characteristic heretofore referred to and thus serves as a stabilizer, as will be more fully gone 75 into.

The condenser 37 has the property of improving the operation of the device by the fact that the voltage across the condenser is instantaneously proportional to the integrated 80 value of the current induced through it, or in other words, the instantaneous voltage which would influence spark-over of gap 36, is proportional to the quantity of current which is passed. Therefore the spark-over characteristics of gap 36, and hence the current limitation characteristics of my device, as a whole, may be directed toward the limitation of the current flow from a quantitative standpoint rather than instantaneous value, which would be the operating characteristic of my invention in the absence of the condenser 37.

With the application of potential from rectifier 13 to the terminals of X-ray tube 95 18, the conductivity of the said tube as fixed by the current limitation characteristics of the cathode heating-current circuits just described, will be fixed independently of whether the temperature of the cathode 34 100 changes inherently, whether the gaseous ionization introduces a disturbing factor, or the specific emission of the filament material changes, or the spontaneous ionization of the tube comes into play as a factor in conductivity, because the thermionic emission of the cathode 34 is saliently the predominating factor in the conductivity of the said tube and sufficient latitude is therefore afforded thereby to hold the aggregate electron emission constant by the adjustment of this one factor, namely; the thermionic emission.

It will be appreciated by those skilled in the art to which my invention appertains 115 that various modifications of my invention may be made without departing from the spirit of my invention such as for example, the use of my device without rectifier 13 and with a different type of X-ray tube 120 and connection with various apparatus such as is common in the art or which may develop in the future.

What I claim is:

1. The combination of an X-ray tube 125 having main electrodes including a thermionic cathode, a main circuit for supplying main energy in cyclic form to said electrodes, an independent circuit including a limited-capacity transformer for supplying 130

heating current for said cathode, and a spark-gap in the main-energy circuit and operatively associated with said transformer, whereby spark-over may occur each cycle across said gap when a predetermined amount of main-energy flows, said spark-over causing additional loading upon said associated transformer, reducing the voltage thereof and thereby limiting the heating current per cycle for said cathode.

2. The combination of an X-ray tube having main electrodes including a thermionic cathode, a main-circuit for supplying main-energy in cyclic form to said electrodes, an independent circuit including a limited-capacity transformer for supplying heating current for said cathode, and a translating device in the main energy circuit having a negative-resistance-characteristic and operatively associated with said transformer, whereby an increase of current in the main circuit causes an increase of loading upon said transformer, thereby limiting the heating current per cycle for said cathode.

3. The combination of an X-ray tube having main electrodes including a thermionic cathode, a main circuit for supplying main-energy in cyclic form to said electrodes, an independent circuit including a limited-capacity transformer for supplying heating current to said cathode, and means common to both main energy circuit and circuit of said transformer comprising a negative-resistance-characteristic load, whereby the increase of current in the main circuit causes an increase of loading upon said

transformer, thereby limiting the heating current per cycle for said cathode.

4. The combination of an X-ray tube 40 having main electrodes including a thermionic cathode, a main circuit including a limited-capacity transformer for supplying heating current for said cathode, and a translating device in the main energy circuit 45 having an abrupt-resistance-breakdown-characteristic and operatively associated with said transformer, whereby the resistance of the said device breaks down abruptly each cycle when a predetermined amount 50 of main-circuit energy flows, causing additional load upon said transformer, thereby limiting the heating current per cycle for said cathode.

5. The combination of an X-ray tube 55 having main electrodes including a thermionic cathode, a main circuit for supplying main-energy in cyclic form to said electrodes, an independent circuit including a limited-capacity transformer for supplying 60 heating current for said cathode, and means in the main energy circuit, operatively associated with said transformer, for causing an abrupt-resistance-breakdown-characteristic 65 load upon said transformer, whereby the resistance of the said means breaks down abruptly each cycle when a predetermined amount of main-circuit energy flows, causing additional load upon said transformer, thereby limiting the heating current per 70 cycle for said cathode.

In witness whereof, I have hereunto set my hand this 10th day of January, 1924.

MONTFORD MORRISON.
